UNITED STATES PATENT OFFICE.

FRANK YOKEL, OF HARTFORD, CONNECTICUT, ASSIGNOR TO DALLAS BRASS & COPPER CO., OF CHICAGO, ILLINOIS, A CORPORATION OF ILLINOIS.

DESIGN FOR A LIGHTING FIXTURE.

Application filed May 2, 1921. Serial No. 466,236. Term of patent 3½ years.

To all whom it may concern:

Be it known that I, FRANK YOKEL, a citizen of the United States, residing at Hartford, in the county of Hartford and State of Connecticut, have invented a new, original, and ornamental Design for a Lighting Fixture (Case F, No. 11,200), of which the following is a specification, reference being had to the accompanying drawings, forming part thereof.

Fig. 1 is a side elevation;

Fig. 2 is a central vertical section of the lower portion of the fixture; and

Fig. 3 is a bottom plan view.

I claim:

The ornamental design for a lighting fixture, as shown.

FRANK YOKEL.
